OTTO B. GOLDMAN, OF PORTLAND, OREGON.

HYDRAULIC BALANCE.

1,095,394.

Specification of Letters Patent.

Patented May 5, 1914.

Application filed April 11, 1913. Serial No. 780,428.

To all whom it may concern:

Be it known that I, OTTO B. GOLDMAN, a citizen of the United States, residing at Portland, in the county of Multnomah and State of Oregon, have invented certain new and useful Improvements in Hydraulic Balances, of which the following is a specification.

This invention relates to an improvement in hydraulic balances, and has for its object to provide means for hydraulically balancing against end thrust, in single suction pumps, in turbines and in single discharge water wheels and the like.

15 A further object is to provide a means in a device of the kind described which is simple and convenient in construction and operation; and to this end it consists in the novel construction, arrangement and combination of parts herein shown and described and more particularly pointed out in the claims.

The objects set forth are accomplished by the structure illustrated in the accompanying drawing, in which—

Figure 1 is a longitudinal sectional view taken on the line $x-x$ of Fig. 2, showing a casing with the interior parts exposed.

Fig. 2 is a transverse sectional view taken 30 on the line $y-y$ of Fig. 1. Figs. 3 and 4 are fragmentary views showing modifications for varying the opening between the shouledered portion of the casing and the runner.

In the preferred form of my device, when 35 used in connection with centrifugal pumps, 1 designates a casing which is approximately spiral, or approximately circular, or disk like in outline, and whose obverse faces are approximately parallel. One of 40 said faces is open at 2 to permit the insertion of the runner or impeller 3, and to afford access to the interior. A closure 4 is fitted into said opening and to it, at a central point, is fixed the inlet pipe 5 which 45 delivers water to the inlet 6 of the runner 3, where it fills the cavities formed between the vanes 7, and by means of which, upon the revolution of the runner, the water is forced into the diffusion chamber 8, formed 50 about the runner, and from which it is driven through the discharge pipe 9 in the periphery of the casing.

Centrally on the face of the casing opposite the opening 2 is formed a two-way boss 55 10, provided with a central aperture 11, in which is mounted the driven shaft 12, carry-

ing the runner 3, to which it is rigidly fixed. In a recess in the boss 10 is secured a stuffing gland 13. This shaft is movable longitudinally, as well as being rotatable in its bearing. Upon the inner side of the rear face of the casing is formed a concentric recess 14, leaving the annular shoulder 15, formed preferably at right angles to said face and parallel with the shaft 12. Upon the adjacent face of runner 3 is formed a concentric annular rib 16, fitted within the shoulder 15, and spaced therefrom. About the shaft 12, on the runner, is formed a boss 17 adapted to be carried against the inner face of boss 10. From the inner face of boss 17 ports 18 lead to the interior of the runner, and so disposed that when the runner is carried against the boss 10 said ports will be thereby closed. From the outer face of the runner is formed a boss 19, which is fitted into the opening 20 of the closure 4, and it is movable therein. This boss is provided with a central aperture 6, registering with pipe 5. The boss 19 is fitted substantially watertight into the opening 20 and thereby reduces the area of the outer face of the runner, which is subject to pressure.

In operation power will be applied to 85 shaft 12 to drive the runner 3, which will force the water therefrom into the diffusion chamber 8, and out through the discharge pipe 9. This will tend to form a vacuum in the central portion of the runner, drawing 90 in water through pipe 5, and creating a suction of the runner toward the outer face of the casing, and tending to cause an end thrust of shaft 5 with the runner. The space between the shoulder 15 and the rib 16 is so gaged as to permit a certain fixed 95 leakage of water therethrough to bear upon the inner face of the runner, but which is free to escape through the ports 18 into the partial vacuum at the center, so as to reduce its pressure upon that side. As the water is forced into the chamber 8 by the motion of the runner, it bears freely on the outer face thereof, which will overcome the suction, or end thrust, and force the runner 100 against the boss 10. This will close the ports 18, when the water on the rear face will exert a forward force on the runner; and since the face of boss 10 has a perceptibly smaller area than that of boss 19, the 110 portion of the inner face still subject to pressure is correspondingly greater than

that of the outer face. The force of the water on the inner face will, therefore, overcome that upon the outer face, and thereby carry the runner away from contact with 5 boss 10 to admit water through the ports 18 and relieve the pressure from the inner face. It will be observed that the longitudinal movement of the shaft 12 is only through a small fraction of an inch. It will 10 be noted also that during such movement, there is no variation in the leakage opening between shoulders 15 and 16, while the space between bosses 10 and 17 varies directly therewith. In this manner the forces on 15 the opposing faces of the runner are made to balance each other. With the slightest movement of the runner away from boss 10, there will be a decrease in the pressure on the inner face, by reason of the escape of 20 the water through the ports; and similarly, any movement in the opposite direction will increase such pressure, by the closing of such ports.

Fig. 3 is a modification, in which the 25 shoulder 15^a is outwardly beveled, and the rib 16^a is made to conform thereto, so that with any longitudinal movement of the shaft 12 the leakage opening will vary with the space between bosses 10 and 17. The 30 angle of said beveled portion made with reference to the face of the recess must be less than an angle whose cosine is the ratio of the distance between the outer sides of the ports in the inner boss to the diameter 35 of the recess; in which case the opening between bosses 10 and 17 will always be greater than the opening between said beveled surfaces at 15^a and 16^a, except when the runner is close to the boss, or at zero 40 distance therefrom, so that when the bosses have approached each other more or less closely, there will be an increase of pressure due to such excess of the leakage at the periphery, which will tend to move the runner toward the suction and thereby relieve 45 any pressure above that necessary to establish a balance under operating conditions and vice versa, when the runner has moved too far toward the suction there will be a 50 reduction of pressure in the recess and on the inner face of the runner, forcing the runner to move away from the suction and toward a point of balance.

In the form shown in Fig. 4 the shoulder 55 15^b is inwardly beveled and the rib 16^b is made to conform with it, so that with longitudinal movements of shaft 12 the leakage space will vary inversely as that between the runner and boss 10.

60 Having now described my invention, what I claim, is—

1. The combination in a centrifugal pump,

or turbine of a casing, a recess in one side having an inclined periphery, a boss formed centrally in said recess, and provided with 65 a central aperture, a shaft mounted in said aperture and movable longitudinally therein, a runner adapted to lie within said recess, and conforming to the periphery thereof, fixed upon said shaft, and having ports 70 leading from points opposite said boss, through its adjacent side member.

2. The combination in a centrifugal pump, or turbine, of a casing a recess formed in one side, the periphery of the recess being 75 formed at an angle with reference to the shaft, a boss having a central aperture formed centrally in the recess, a shaft mounted to rotate in said aperture and movable longitudinally therein, an impeller 80 fixed upon said shaft, one side of which is fitted within said recess conforming to said periphery and having ports leading through said side at points opposite said boss, whereby upon longitudinal movement of 85 the shaft said ports may be closed and opened, and the ratio of the area between the periphery of the recess and said runner to the area between said central boss and said runner will decrease as the runner 90 moves toward the suction and vice versa the ratio will increase as the runner moves away from the suction.

3. The combination in a centrifugal pump, or turbine, of a casing, a recess formed in 95 one side thereof, a boss having a central aperture formed centrally in the recess, the periphery of the recess being formed at an angle to the face thereof which is less than an angle whose cosine is the ratio of the 100 distance between the outer sides of the ports in said boss to the diameter of said periphery, a shaft mounted to rotate and movable longitudinally therein, an impeller fixed upon said shaft one side of which is fitted 105 within said recess conforming to said periphery and having ports leading through said side at points opposite said boss, whereby, upon longitudinal movement of the shaft said ports may be closed and opened, 110 and the ratio of the area between the periphery of the recess and said impeller to the area between said central boss and said impeller will decrease as the impeller moves toward the suction and vice versa, the ratio 115 will increase as the impeller moves away from the suction.

In testimony whereof I affix my signature in presence of two witnesses.

OTTO B. GOLDMAN.
